UNITED STATES PATENT OFFICE.

FREDERIK ISHÖY, OF COPENHAGEN, DENMARK, ASSIGNOR TO AKTIESELSKABET KAPTAJN ISHOY'S NY SKIBSTYPE, OF COPENHAGEN, DENMARK.

MEANS FOR PROPELLING VESSELS.

No. 923,123.

Specification of Letters Patent. Patented May 25, 1909.

Original application filed April 20, 1904, Serial No. 204,144. Divided and this application filed September 7, 1905. Serial No. 277,286.

To all whom it may concern:

Be it known that I, FREDERIK ISHÖY, subject of the King of Denmark, residing at Copenhagen, in the Island of Seeland and 5 Kingdom of Denmark, have invented certain new and useful Improvements in Means for Propelling Vessels; and I do hereby declare the following to be a full, clear, and exact description of the invention, such as will enable 10 others skilled in the art to which it appertains to make and use the same.

This invention relates to improvements in means for propelling vessels or for reducing the resistance to the progress of vessels 15 by aid of pressure exercised from below against the aft half of the ship's bottom by the flow from the propellers, and by aid of enveloping the stern entirely into this flow in order to prevent the resistance to the 20 progress of the ship, which is caused by the wake-wave.

Another purpose of this invention is to protect the screws in vessels of the kind indicated above by means of channels under the 25 bottom of the ship, which channels, however, must be so broad as to allow a satisfactory development of the flow from the propellers.

The present application is a division of prior application No. 204,144, filed April 20, 30 1904.

In the accompanying drawing, Figure 1 shows a ship the screws of which are distributed only along the aft half of the bottom. Fig. 2 shows a vessel with a greater 35 number of screws distributed along the aft half of the bottom, several propeller shafts and a few counterbalancing propellers under the fore part, it being supposed, that the pressure under the aft part has become too 40 strong. Fig. 3 is a view of Fig. 2 from below, Fig. 4 shows Fig. 3 from behind, Fig. 5 shows Fig. 1 from behind, Fig. 6 shows from behind a ship in which the channels are formed by rails.

In Fig. 1 *a* is the ship's bottom, *b* an under boat containing the machinery and crank shaft, *c* the propeller shaft penetrating one end of the underboat and tightened by a packing box, *d* are the propellers. The propeller shaft may under the ship's bottom be supported by one or several bearing stands. At a suitable distance from the propeller shafts are provided downward projecting parts *e* under the ship's bottom, to be seen 55 in Fig. 5. These projections protect the

screws against damage. The channels are usually enlarged considerably toward the stern, as shown in Fig. 3, that the flow from the propellers may envelop the stern entirely. The cross section of the channels 60 may be the same along the whole length, or it may be narrower under the fore half of the ship.

In Fig. 2 are shown five propellers each on its shaft, under the aft part and two propellers under the fore part of the ship, as it is supposed, that the pressure under the aft part has become too strong and therefore must be counterbalanced by a suitable number of counterbalancing propellers under 70 the fore part of the ship. Only in this case screws under the fore part of the ship may be allowed. The propeller shaft *c* projects from the underboat *b* on both ends and is likewise tightened by packing boxes. The downward projecting parts *e* of the hull are situated in a similar manner as in Fig. 1, and the channels may also be enlarged toward the stern. Of course it may be permissible to provide two or more propeller shafts and 80 channels under the ship's bottom. It may also be permissible to provide two or several propeller shafts in a single channel.

In Fig. 3 are shown two propeller shafts and channels under the same vessel. The 85 number and arrangement of the propellers are the same as in Fig. 2. The channels may be broader under the aft part of the ship than under the fore part or be of the same breadth as shown in dotted lines, they may be enlarged toward the stern as shown in the drawing. The projecting part in the middle of the bottom which is indicated in dotted lines may be employed or not. The channels for conducting the flow from the propellers 90 may also be formed by rails *e*, as shown in Fig. 6. In this way the channels become considerably broader and the flow from the propellers is utilized considerably better than in the foregoing figures.

What I claim is:

1. In ships, the combination of a bottom formed relatively broad and flat over all its length from bow to stern and merging into the bow and stern by a rounded outline and 105 provided with longitudinal projecting parts forming a relatively very broad and flat-bottomed channel extending from stem to stern and including the greater part of the area of the ship's bottom, an underboat, a 110

driving device placed in said underboat, and a plurality of relatively small propellers operated by said device and arranged under the bottom and distributed unsymmetrically to 5 the center of gravity of the ship along the aft part of the vessel in the channel close to said bottom, said propellers being adapted to suck the water in front of the stern downward into and through the channel and lead 10 it to the stern, this diminishing the pressure in front by the propeller suction, and increasing the pressure under the aft half of the vessel, and eliminating the vacuum at the stern by the pressure from the propellers.

15 2. In ships, the combination of a bottom formed relatively broad and flat over all its length from stem to stern, and merging into the bow and stern by a rounded outline, and provided with longitudinal projecting parts 20 forming a channel extending from stem to

stern and including the greater part of the area of the ship's bottom, an underboat, a driving device placed in said underboat, and a plurality of relatively small propellers operated by said device and distributed unsymmetrically, a preponderating number of said propellers being arranged behind the center of gravity of the ship in the channel under the bottom, and the remainder in front of the center of gravity, to counter-balance a surplus of pressure exercised under the aft half by a suitable pressure under the fore half of the vessel.

In testimony whereof, I have signed my name to this specification in the presence of 35 two subscribing witnesses.

FREDERIK ISHÖY.
